SHOE WITH RESILIENT CLOSURE MEANS

Charles A. Juliuson, Fort Worth, Tex.

Application January 29, 1946, Serial No. 644,073

2 Claims. (Cl. 36—50)

1

This invention relates to shoe construction and it has particular reference to closure devices therefor, and its principal object resides in the provision of a shoe structure whereby conventional laces, and other types of common retaining mediums, can be eliminated.

An object of the invention is that of providing a shoe construction which embodies a tensioned closing means for the opening or placket in the upper to facilitate the donning or doffing of the shoes, and avoid the necessity for lacing or otherwise fasten the same, and afford an efficient and comfortable means for securing the same upon the wearer's feet.

Broadly, the invention seeks to comprehend the provision of a fastening device for shoes which affords a practical and desirable means for retaining the shoes while presenting a more attractive foot dress.

While the foregoing objects are paramount, other and lesser objects will become manifest as the description proceeds, taken in connection with the appended drawings wherein:

Figure 1 is a perspective illustration of the spring element for closing the shoe and retaining the same.

Figure 2 is a perspective illustration of a shoe having its upper formed with rolled and stitched edges or tunnels along the placket thereof, a portion of one being shown cut away to illustrate the position of the spring element therein.

Figure 3 fragmentarily shows a form of upper in which the rolled edges are unsecured and showing the spring element thereunder in dotted lines.

Figure 4 is a lateral cross-sectional view across the instep, taken on lines 4—4 of Figure 3, illustrating the outwardly rolled substantially tubular tunnels forming pockets removably receiving the parallel prongs of the spring element, and

Figure 5 is a lateral cross-sectional illustration, taken on lines 5—5 of Figure 2, showing the rolled edges forming substantially tubular tunnels and stitched to the upper and encasing the spring element.

Accordingly, the invention comprises a spring closing element 10 which is preferably of spring steel and thus highly tensile. Its form, as in Figure 1, defines a substantial ring 11 at its lower end from which extends a pair of spaced parallel prongs 12 which turn outwardly and upwardly and are slightly curved at their upper ends 13.

The upper 14 of the shoe 15, along the edges 16 of the placket 17 in the front thereof, is formed with outwardly rolled portions 18 which

2

extend upwardly from the toe cap 19 to the top 20 and rearwardly therealong terminating over the instep portion 21, as in Figure 2. This arrangement defines substantially tubular tunnels 5 in which the parallel prongs 12 of the spring element 10 are arranged, as shown in Figure 2, the ring portion 11 of the latter being arranged about the lower end of the placket 17 and encased by a flap 22. The upper ends 13 of the prongs 12 ranging back along the rim of the upper 14 and conforming to the contour of the ankle.

Obviously, the spring element 10, when properly formed and of suitable tensioned material, will yieldably retain the placket 17 securely 15 closed and the shoe 15 may be removed from the wearer's foot by slipping it off without unfastening the same.

The invention may be constructed to embody a form whereby the spring element 10 can be made 20 detachable or replaceable, as in Figures 3 and 4, by forming the tunnels in which the spring element 10 is arranged without securing the outer edges 6 of the rolls 18 thus providing open channels 23 through which the parallel prongs 12 of the spring element 10 can be inserted. The rolls 18 are preferably hardened, as in the conventional manner of constructing counters or toe caps, to provide suitable containers for the spring 10.

If desirable a small coil spring, or other type of tensioned device, may be connected across the prongs 12 near the ring portion 11 to increase the tension of the spring 10 or strengthen the same. Such a device would be arranged across 35 the lower end of the placket 17.

Manifestly, the structure herein shown and described is capable of considerable changes and modifications by persons skilled in the art without departing from the spirit and intent of the invention or the scope of the appended claims.

I claim:

1. In a shoe construction having an upper with an opening formed in its front instep portion, in combination, opposing channels formed along the edges of said instep portion on each side of said opening and extending rearwardly from the top of said opening along portions of the top of said upper, a substantially U-shaped tensioned member arranged in said channels and having the upper extended ends of the spaced parallel legs of said member oppositely extended along the portions of said channels formed in the top of said upper.
- 45 2. In a shoe construction having an upper and an opening in the instep portion thereof, in com-

bination, opposing channels formed along each edge of said opening by rolling said edges and the top rim of said upper back upon the body thereof, said channels being thus extended to parts of said rim of said upper, a dual pronged tensioned member having spaced parallel legs arranged in said channels whereby said opening is normally closed under tension, portions of the upper ends of said tensioned member being turned at right angles to said legs and extending oppositely and rearwardly in said extended portions of said channels.

CHARLES A. JULIUSON.
